UNITED STATES PATENT OFFICE.

WILLIAM F. RAY AND ROBERT BONNETT, OF SAMOA, CALIFORNIA.

BOILER FUSIBLE PLUG.

1,237,957.

Specification of Letters Patent.

Patented Aug. 21, 1917.

Application filed April 9, 1915. Serial No. 20,313.

To all whom it may concern:

Be it known that we, WILLIAM F. RAY and ROBERT BONNETT, citizens of the United States, residing at Samoa, in the county of Humboldt, State of California, have invented a new and useful Boiler Fusible Plug, of which the following is a specification.

The device forming the subject matter of this application is a soft plug for crown sheets, boilers and the like, and in order that the advantages of the present invention may be apparent readily, it is necessary to comment briefly upon devices of this sort as disclosed in the prior art.

In one form of plug of the sort herein described, a thimble, carrying a mass of fusible metal, is threaded into the crown sheet or boiler directly. It is required by boiler inspection regulations that the thimble or plug shall project into the water a certain specified distance, and as a consequence, the projecting end of the thimble soon becomes incrusted with lime or other material derived from the water. When the thimble is threaded out of the crown sheet or boiler shell, the deposit on the thimble frequently destroys the threads in the crown sheet or shell to such an extent that the thimble receiving opening must be rethreaded and, frequently, it is necessary to make a special thimble or plug in order that the same may cooperate properly with the rethreaded opening.

In view of the foregoing, one object of the present invention is to provide novel means whereby the threads of the thimble, upon that end of the thimble which projects into the water, will be protected.

In devices of this sort, the fire end of the thimble which carries the fusible metal, generally projects into the furnace and soon becomes deteriorated to such an extent that the thimble or plug cannot be threaded out of the shell by applying a wrench to that end of the thimble which projects into the furnace.

Another object of the invention, therefore, is so to house and protect the fire end of the thimble which carries the fusible metal, that the thimble may at all times be threaded out without difficulty, the fire end of the thimble being so constructed that such a result may be brought about.

In order that the thimble may be rotated readily, the same is provided at its fire end

with a kerf adapted to receive a heavy screw-driver or like tool. The mass of fusible metal in the thimble is set back from that end of the thimble which carries the kerf and as a consequence, the end of the mass of metal is not intersected by the kerf. One end face of the mass of metal, therefore, remains continuous and unbroken and is adapted to receive an inspection stamp which commonly is placed upon both ends of the mass of metal. Further, owing to the fact that one end of the mass of metal is set back from the fire end of the thimble as hereinbefore stated, the stamp receiving face is not presented prominently to the fire and the stamp will not be likely to be obliterated.

The invention, generally considered, aims to provide a means for protecting the threads on that end of the thimble which projects into the water space, to provide novel means for alining one end face of the thimble and one end of the socket with the fire surface of the crown sheet or shell, to provide novel means whereby the thimble may be rotated out of the socket, and to provide a device of the sort above mentioned in which one stamp receiving end face of the mass of fusible metal is shielded and protected against deterioration due to furnace heat.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows the invention in longitudinal section;

Fig. 2 is a bottom plan;

Fig. 3 is an elevation of a tool employed for seating the socket in place.

In the accompanying drawings, the numeral 1 indicates a portion of a crown sheet, the water side of which is denoted by the numeral 3 and the fire side of which is denoted by the numeral 2.

The numeral 4 indicates a socket which

preferably is fashioned from steel or iron. The socket 4 is externally threaded as shown at 5 to engage with the crown sheet 1 and may if desired have a slight external taper as clearly shown in Fig. 1. In one end of the socket 4 there is formed a recess 6, defining within the contour of the socket, a circumscribing shoulder 7. Beyond the shoulder 7, the bore of the socket 4 is reduced in diameter, tapered and threaded as shown at 8.

The invention comprises a thimble 9 having a tapered bore 10. At one end, the thimble 9 is provided with an enlarged head 11 received in the recess 6 of the socket. Beyond the head 11, the thimble 9 is tapered to form a neck 14 threaded to engage with the threaded portion 8 of the bore of the socket 4. The thimble 9 may be made of brass or some other metal which expands at a lower degree of heat than does the metal out of which the socket 4 is made.

Located in the bore 10 of the thimble 9 is a mass of fusible metal indicated at 15. In one end of the thimble 9 there is formed a kerf 16 adapted to receive a heavy screw-driver or like tool. One end face 17 of the mass 15 of fusible metal is set back from the fire surface 2 of the crown sheet to a point adjacent the base of the kerf 16. The end face 17 of the mass of metal, therefore, is not intersected by the kerf 16 and remains continuous and unbroken, the end face 17 as well as the opposite end face of the mass 15 of fusible metal 15 being adapted to be stamped as is the common custom with boiler inspectors.

An important although not mandatory adjunct to the present invention is disclosed in Fig. 3, wherein there appears an applying member 18 having a threaded portion 19, a shoulder 20 and a wrench head 21.

In assembling the invention with the crown sheet 1 as shown in Fig. 1, the socket 4 is threaded onto the part 19 of the applying member 18, the shoulder 20 in the applying member abutting against the shoulder 7 in the socket. A wrench is then applied to the head 21 and the socket is threaded into the crown sheet as shown in Fig. 1, until one end of the socket is flush with the fire surface 2 of the crown sheet. The applying member 18 then is removed from the socket. Thereupon the thimble 9 is threaded into the socket, a screw-driver or like tool being inserted into the kerf 16, the tapered, threaded neck 14 of the thimble binding tightly in the tapered, threaded bore 8 of the socket and the end face 12 of the thimble being disposed approximately flush with the corresponding end face of the socket and with the fire surface 2 of the crown sheet 1. The parts thereupon will appear assembled as shown in Fig. 1.

Since the thimble 9 is fashioned from

some metal which expands more readily under heat than does the metal out of which the socket 4 is formed, the head 11 of the thimble will soon acquire, under heat expansion, a tight fit against the lateral wall 70 of the recess 6.

The threads on the exterior of the thimble 9 are protected by the socket 4 and cannot become encrusted with lime or the like. Therefore, the removal of the thimble 9 is 75 a matter which can be carried out without difficulty.

Owing to the fact that one end face of the thimble 9 and the corresponding end face of the socket 4 are flush with the fire surface 80 2 of the crown sheet 1, there are no parts projecting into the furnace and likely to melt or become deteriorated, especial attention being directed to the manner in which the kerf 16 is housed and protected. 85 The end face 17 of the mass 15 of fusible metal is set back from the fire surface 2 of the crown sheet and will not deteriorate due to heat and, it is to be noted, the said end face 17 is not intersected by the kerf 16 90 and therefore remains continuous and unbroken, and is well adapted to receive an inspection stamp.

It will be obvious to those skilled in the art that the entire structure shown in Fig. 1 95 will be employed in inverted position if the water is below the sheet 1 and the fire is above the sheet.

Having thus described the invention, what is claimed is:

1. In a device of the class described, a crown sheet having a threaded opening; a socket externally threaded to coöperate with the threaded opening in the crown sheet and having its fire end disposed flush with the fire side of the crown sheet, the socket being provided in its water end with a threaded bore, and being provided in its fire end with an enlarged, smooth, cylindrical recess defining a shoulder adapted to receive an applying tool whereby the socket may be threaded into the opening in the crown sheet; a thimble having a screw driver kerf in its fire end and having a flaring bore, the thimble being provided at its fire end with a smooth head received in the recess and flush with the fire end of the socket, the thimble being externally threaded to coact with the threaded bore of the socket; and a mass of fusible metal located in the bore of the thimble and terminated adjacent the base of the screw driver kerf.

2. In a device of the class described, a crown sheet having a threaded opening which is tapered from the fire side of the sheet to the water side thereof; a socket externally threaded and tapered continuously from its fire end to its water end, the socket being mounted in the threaded opening of the crown sheet and having its fire end dis-

posed flush with the fire side of the crown sheet, the socket being provided in its water end with a tapered threaded bore, and being provided in its fire end with an enlarged, smooth, cylindrical recess defining a shoulder adapted to receive an applying tool whereby the socket may be threaded into the opening in the crown sheet; a thimble having a screw driver kerf at its fire end and 10 having a bore, the thimble being provided at its fire end with a smooth head received in the recess and flush with the fire end of the socket, the water end of the thimble ter-

minating in a tapered, externally threaded neck coacting with the tapered bore of the 15 socket; and a mass of fusible metal located in the bore of the thimble and terminated adjacent the base of the screw driver kerf.

In testimony that we claim the foregoing as our own, we have hereto affixed our signatures in the presence of two witnesses.

WILLIAM F. RAY.
ROBERT BONNETT.
